UNITED STATES PATENT OFFICE.

WILLIAM MERZ, OF NEW YORK, N. Y., ASSIGNOR TO WESTERN ELECTRIC COMPANY,
OF CHICAGO, ILLINOIS, A CORPORATION OF ILLINOIS.

FUSE-MOUNTING.

971,205.

Specification of Letters Patent. Patented Sept. 27, 1910.

Application filed October 28, 1907. Serial No. 399,417.

To all whom it may concern:

Be it known that I, WILLIAM MERZ, citizen of the United States, residing at New York, in the county of New York and State 5 of New York, have invented a certain new and useful Improvement in Fuse-Mountings, of which the following is a full, clear, concise, and exact description.

My invention relates to a mounting for 10 fuses, and its object is to provide an efficient and satisfactory mounting which is of simple construction and which may be cheaply manufactured.

I will describe my invention and also the 15 method of manufacturing the same by reference to the accompanying drawings, in which—

Figure 1 is a plan view of the molding apparatus showing a plurality of fuse 20 mountings held therein in the manner in which they are assembled in their manufacture; Fig. 2 is a side elevation of the structure shown in Fig. 1; Fig. 3 is a vertical sectional view on the line 3—3 of Fig. 1; and 25 Fig. 4 is a longitudinal central section of the fuse mounting of my invention.

Similar letters of reference are used to designate similar parts wherever shown.

The fuse 1 is inclosed in a tubular shell 30 2 of refractory insulating material, such as porcelain, which is provided with metallic caps or heads, 3, 3, molded about its ends. Each terminal of the fuse mounting consists of a threaded bolt 4 having a longitudinal 35 hole 5 therein to receive the end of the fuse 1, said fuse being electrically connected to the bolt by being soldered or otherwise suitably secured within the hole 5. One end of the bolt 4 abuts against the tubular shell 2 40 about the opening therein, the hole 5 being in alignment with the opening through the shell 2. Said bolt 4 is secured in position by the metallic cap 3. The projecting end of the bolt 4 is adapted to receive nuts 6, 6, for 45 securing the mounting in position in the usual manner. Each cap 3 is made of a suitable alloy, which, after the bolt 4 is assembled in proper relation to the shell 2, is molded about the end of the shell, said shell 50 being knurled or otherwise provided with indentations 7, 7, with which the caps interlock to prevent said caps from coming off.

The fuse mounting of my invention is thus of simple construction, not liable to damage

in handling, and may be cheaply manu- 55 factured.

Suitable apparatus for assembling and uniting the several parts are shown in Figs. 1, 2 and 3. A horizontal block 8 is provided at intervals along its longitudinal center 60 with depressions or cavities 9. At the center of each cavity is a vertically extending hole 65 adapted to receive the bolts 4, which extend therethrough and rest upon the stop 10 which extends longitudinally beneath the 70 block 8, the upper ends of said bolts extending above the bottoms of the cavities 9. The sleeves 2 rest upon the ends of the bolts 9. The upper ends of said sleeves are held by 75 spring clips 11, mounted on a plate 12, which in turn may be mounted on standards extending from a clamping jaw 13. The two clamping jaws 13, 14, are pivotally mounted 80 upon the block 8, and when said jaws are closed their edges meet upon a line through the center of said depressions or cavities 9. Each jaw 13, 14, is provided, immediately 85 above the depressions 9, with semi-circular indentations of such dimensions that said jaws, when closed, clamp the shells 2 and center them upon the bolts 5. Said jaws when closed form a top to the mold provided by the depressions 9. The jaw 14 is provided with funnel-shaped depressions 15 for admitting the molten metal which is poured 90 into the cavity to form the cap 3. The cavity 9 is slightly tapered at the bottom to facilitate the withdrawal of the cap 3 from said cavity, and when the jaws are moved apart the fuse mounting may be readily removed.

I claim:

1. In a fuse mounting the combination with a tubular shell, a terminal bolt at the end of said shell adjacent the opening therethrough, a fuse wire passing through said shell and having its end electrically connected to said bolt, and a molded metal cap upon the end of said shell securing said bolt thereto.

2. In a fuse mounting the combination with a tubular shell, of a molded metal cap about the end of said shell, a terminal bolt embedded in said cap, and a fuse wire passing through said shell and electrically connected to said bolt.

3. In a fuse mounting the combination with a tubular shell, of a molded metal cap

about the end of said shell, a terminal bolt embedded in said cap, said bolt having a hole therein, and a fuse wire passing through said shell and having its end secured in the hole in said bolt.

4. In a fuse mounting the combination with a tubular shell, of a terminal bolt at the end of said shell adjacent the opening therethrough, said bolt having an opening 10 in alinement with the opening through said shell, a fuse wire passing through said shell into the opening in said bolt and connected to said bolt, and a molded metal cap upon the end of said shell securing said bolt thereto.

5. In a fuse mounting the combination with a tubular porcelain shell, of a fuse wire passing through said shell, a terminal

bolt at the end of said shell to which said fuse wire is connected, and a molded metal 20 cap about the end of said shell, said bolt being embedded in said cap.

6. In a fuse mounting the combination with a tubular porcelain shell, of a terminal bolt, a fuse wire passing through said shell 25 electrically connected to said terminal bolt, and a molded metal cap surrounding the end of said shell and securing said bolt thereto.

In witness whereof, I hereunto subscribe 30 my name this 23 day of October A. D., 1907.

WILLIAM MERZ.
